UNITED STATES PATENT OFFICE.

WILLIAM SAINT GEORGE ELLIOTT, JR., OF NEW YORK, N. Y.

ARTIFICIAL TOOTH AND DENTURE.

1,209,570.

Specification of Letters Patent. Patented Dec. 19, 1916.

Application filed January 20, 1916. Serial No. 73,134.

To all whom it may concern:

Be it known that I, WILLIAM SAINT GEORGE ELLIOTT, Jr., a citizen of the United States, residing at New York, in the county 5 of New York and State of New York, have invented certain new and useful Improvements in Artificial Teeth and Dentures; and I hereby declare that the following is a full, clear, and exact description thereof, reference being had to the accompanying drawings, which form part of this specification.

This invention is a novel improvement in artificial dentures. Its objects are to provide a novel strong and durable means for 15 attaching artificial or porcelain teeth to a backing bridge or plate; and to provide a simple form of so called removable teeth for artificial dentures, and one that is better adapted to modern casting methods than 20 those now in use.

The invention relates especially to that class of artificial teeth which are fastened to the bridge or plate after the latter is made; and may be used with whole teeth, or with 25 only the fronts or visible portions of the teeth.

The invention is also particularly designed for use with what are sometimes called removable teeth and provides novel 30 means whereby such teeth can be readily secured in place; such attaching means being simple, easily made, very strong, and adaptable to modern dental requirements.

I will explain the invention, with reference 35 to the accompanying drawings, so that others will be able to understand and use the same; and the essential features and combinations of parts for which I desire protection are set forth in the claims following the description.

In said drawings: Figure 1 is a longitudinal section of an artificial cuspid tooth comprising a facing and backing, as attached to a plate or bridge. Fig. 2 is a rear elevation 45 of the facing in Fig. 1. Fig. 3 is a side elevation of the backing in Fig. 1. Fig. 4 is a front elevation of the backing in Fig. 1. Fig. 5 is a longitudinal section of a bicuspid tooth and its backing. Fig. 6 is a front elevation 50 of the backing in Fig. 5. Fig. 7 is a detail sectional view of a plate or bridge showing how the backing may be formed integral therewith. Fig. 8 is a detail sectional view, similar to Fig. 7, showing another slight modification of the invention.

As shown in the drawings the tooth or facing 1 may be made of porcelain or other

suitable material and is flattened on its rear face or part which is attachable to the bridge or plate; and in said rear portion is 60 formed a preferably annular groove 3 adapted to engage a correspondingly shaped male member or collar on the backing, bridge or plate, as hereinafter explained. The tooth is also preferably provided in its rear with 65 a shallow recess 4 larger in extent than the diameter of the recess 3; the exterior rear edge of the tooth surrounding said recess 4 being flat on its rear face to enable it to be closely fitted against the face of the backing, 70 bridge or plate to which the facing or tooth is to be secured. The grooves in the teeth can be very easily and cheaply made of the correct size during the forming of such teeth.

The metal backing 2 is made separate from the tooth and can also be made separate from the bridge or plate if desired and rigidly secured thereto. If the bridge or plate is made of metal the backing can be 80 made separate and soldered thereto; or if the bridge or plate is cast the backing can be formed as an integral part of the bridge or plate; or united therewith during the casting operation, in the well known manner. An 85 essential part of the backing is the male-member or collar 5 which is shown in the form of an annular collar or tube corresponding in form to the groove 3, into which such collar is adapted to neatly fit as shown; 90 and the opposed faces of the groove 3 and collar or member 5 are rigidly united by any suitable cement. I preferably employ a plastic cement which may be placed in the groove 3 before the tooth is applied to the 95 collar.

The shallow recess 4 on the back of the tooth allows the edge of the rear face of the tooth to be fitted closely and accurately against the backing, bridge or plate; and 100 the groove and collar form a close, perfect and rigid joint between the tooth and backing, bridge or plate. In a joint of this nature, it is advisable to have as great a surface for adhesion of cement as possible and 105 for this purpose the groove 3 is shown as preferably circular in form, but I do not consider the invention restricted to a truly cylindric recess; but it is an object of the invention to obtain as large an amount of 110 superficial surface for adhesion of cement on the opposed walls of the recess and collar as is practical; to enhance the solidity of engagement of the tooth with the collar,

and the form of collar and groove shown insures great strength and rigidity in the connection between the tooth and backing, bridge or plate. The said collar 5 should 5 be made as thin as consistent with safety and should fit neatly in the groove 3; but enough space may be left between the inner surface of the collar 5 and the inner wall of the groove for any surplus cement to escape 10 when the facing or tooth is put in place; suitable openings may be also provided as at 6, in collar 5, to permit excess cement to escape from within the collar into the outer portion of recess 4.

15 The collar 5 on the backing, bridge or plate should be located in proper place thereon to suit the particular kind of tooth which is to be secured in place. Thus for a cuspid tooth the collar would preferably 20 be located at about the center of the backing as in Figs. 1-4; for a bicuspid tooth the collar would preferably be located near one end of the backing as in Figs. 5 and 6. It is obvious that in applying the invention 25 to a bridge or plate the number of collars or backings attached to or formed on such plate or bridge should correspond in number and position with the teeth which are to be attached thereto. Where the plate or 30 bridge is molded of rubber or composition or is cast of metal, the collars may be formed of sections of a suitable metallic tubing as indicated at 5' in Fig. 7, and 5^b in Fig. 8; which sections can be placed in position in 35 the mold previous to casting or molding the bridge or plate. Where such bridge or plate is cast the inner end of the tube will be welded or rigidly united to the body of the metal, and practically becomes an integral 40 part thereof as indicated in Fig. 7. In actual practice the collar may be about five thousandths of an inch in thickness; and the groove 3 slightly wider than the thickness of the collar, and about one twentieth 45 of an inch deep, the small amount of metal used in the collar is of practical importance when it is made of gold alloy. As the collar is of annular form it can be made quite thin and at the same time give great rigidity. When a porcelain tooth is properly cemented to such a collar it is practically impossible to remove such tooth without breaking 50 it.

In inventions of this nature the parts are 55 frequently manufactured and sold separately; that is the facings and backings or collars may be sold separately, or in conjunction, but when such parts are sold separately they will be assembled with the other 60 parts by the dentists. The essential features of the invention are an artificial tooth having a front resembling a natural tooth, a flat back and an annular groove in the

back adapted to engage a similar male portion attached to the backing or denture to 65 secure said facing thereto.

What I claim is:

1. An article of manufacture consisting of an artificial tooth having a front resembling a natural tooth, and a flat back provided with an annular groove adapted to 70 engage with a similar male portion attached to the denture, to hold said facing to the denture.

2. An article of manufacture consisting of 75 a metal backing having an annular metal collar on its front face, adapted to fit into an annular groove in a facing to hold the facing.

3. The combination of an artificial tooth 80 having a front resembling a natural tooth and provided with an annular groove in its back; with a supporting member having an annular collar on its front face adapted to enter said recess whereby said tooth is 85 secured to a denture.

4. An artificial tooth having a front resembling a natural tooth, a shallow recess in its back and a deeper groove in said recess; with a plate or bridge and a male member on 90 said plate or bridge adapted to enter said groove to secure said tooth thereto.

5. An artificial denture comprising a support having a flat surface and an annular collar projecting from said flat surface, and 95 an artificial tooth or facing having a flat back, and an annular groove in said back corresponding with and adapted to engage the collar on the denture, said collar having openings for the escape of surplus cement. 100

6. An artificial denture comprising a support having a flat surface and a male member projecting from said flat surface; and an artificial tooth or facing having a flat back, a shallow recess therein and a groove 105 in said recess corresponding in contour with and adapted to engage the male member.

7. An artificial denture comprising a support having a flat surface and an annular collar projecting from said flat surface; and an artificial tooth or facing having a flat back, a shallow recess therein, and an annular groove in said recess corresponding with 110 and adapted to engage the collar.

8. An artificial denture comprising a support having a flat surface and an annular collar projecting from said flat surface; and an artificial tooth or facing having a flat back, a shallow recess therein, and an annular groove in said recess corresponding with 115 and adapted to engage the collar, said collar having an opening for the escape of surplus cement.

In testimony that I claim the foregoing as my own, I affix my signature.

WILLIAM SAINT GEORGE ELLIOTT, JR.
